UNITED STATES PATENT OFFICE.

WILLIAM M. BAUMHECKEL, OF CINCINNATI, OHIO.

VALVE MECHANISM FOR INTERNAL-COMBUSTION ENGINES.

1,220,814.

Specification of Letters Patent. Patented Mar. 27, 1917.

Application filed February 6, 1914. Serial No. 817,045.

To all whom it may concern:

Be it known that I, WILLIAM M. BAUMHECKEL, a citizen of the United States, residing at Cincinnati, in the county of Hamilton and State of Ohio, have invented certain new and useful Improvements in Valve Mechanisms for Internal-Combustion Engines, of which the following is a specification.

10 My invention relates to improvements in combustion engines. One of its objects is to provide an improved rotary valve mechanism to control the fuel intake and exhaust. Another object is to provide a practically noiseless valve mechanism. Another object is to provide a readily accessible valve mechanism, and one which is simple in its construction and adjustment, and readily renewable in whole or in part, to enable the 20 engine to be more readily kept in perfect operating condition. Another object is to provide improved means to secure tight joints between the valve and stationary ports. Another object is to provide an improved balanced or equalizing rotary valve. Another object is to provide improved means to regulate or adjust the valve relative to its casing and to lubricate the valve. Another object is to provide for 30 maintaining the valve at low and even temperature. Another object is to provide an improved combination of rotary valve, cylinders, ports and valve supporting and driving mechanism. My invention also comprises certain details of form, combination, and arrangement, all of which will be fully set forth in the description of the accompanying drawings, in which:

Figure 1 is a sectional view on line $v v$ of Fig. 2 illustrating my improved valve applied to control the fuel supply and exhaust of two cylinders of a four cylinder engine.

Fig. 2 is a top plan view of the cylinders and valve chamber with the valve removed.

45 Fig. 3 is an inside plan view of the valve chamber cap.

Fig. 4 is a perspective view of the rotary valve detached.

50 Fig. 5 is a perspective view of one of the valve port sealing rings detached.

Fig. 6 is an enlarged top plan view of the cylinders and valve chamber with the valve in place.

55 Fig. 7 is a section on line $w w$ of Fig. 6 with the valve and cap in place.

Fig. 8 is a central horizontal section through the valve Fig. 4.

Fig. 9 is an enlarged sectional detail of one of the ports and its sealing ring and illustrating a modification.

Fig. 10 is a vertical section through the cylinder and valve chamber on line $z z$ of Fig. 11, and illustrating a modification in which the valve is of non-compensating type.

Fig. 11 is a top plan view of the cylinder 65 and valve chamber casting Fig. 10 with the cap and valve removed.

Fig. 12 is a view similar to Fig. 8 illustrating a modification of the valve to rotate at half engine speed.

The accompanying drawings represent the preferred embodiment of my invention in which A A' represent two cylinders of a combustion engine preferably cast integral with a water jacket B surrounding a portion 75 of each cylinder and a portion of the valve chamber or casing C and also serving to cool the journal 2 of the valve stem or shaft D. The two cylinders illustrated are designed to be used in connection with two 80 similar cylinders in a four cylinder engine for driving an automobile or similar purpose. I contemplate the use of my improved valve mechanism, however, in connection with single cylinder engines, and also with 85 engines of any desired number of cylinders requiring only obvious changes in the location of the valve ports to correspond to the number of cylinders employed.

I preferably employ a hollow valve E presenting two opposite disk-like faces, 5 and 6 rotating close to, but slightly out of contact with, corresponding inner walls, 7 and 8, of the valve casing, which is preferably 90 an annular or cylindrical chamber formed partly in the cylinder casting over the cylinder heads, and closed at the top by a cap 9. Beneath the valve casing is a tube or sleeve 10 provided with a rigidly mounted journal or bearing 2 to rotatably support the valve 95 stem D. The bearing 2 is adjustable vertically to support the valve slightly out of contact with the inner face of the chamber by means of one or more detachable washers placed beneath said bearing. In order to 100 accurately and conveniently align the faces of the valve and valve chamber the lower bearing 3 is preferably mounted in a casing L which is adjusted relative to the cylinder casting until the valve E travels true with 110

reference to the inner face of the valve chamber, whereupon said casing is rigidly bolted to the cylinder casting and when the cylinder casting and crank casing are assembled, said casing L is designed to pass through and accurately register with a hole bored therefor in the crank casing at the desired distance to one side of the crank shaft axis, thereby insuring ready assembling of the parts for the gears to accurately mesh and be firmly supported. The weight of the valve is supported upon the cone or rotary member of the bearing 2 by means of a hub 11 carried by the valve and to which the valve stem D is keyed or rigidly secured. The journal 2 is vertically adjustable so as to support the valve slightly above and out of contact with the lower face of the valve casing, and so as also to be slightly out of contact with the under face 8 of the cap 9 thereby enabling the valve to rotate freely within the casing and out of contact with the walls thereof. The valve is preferably driven directly from the main crank shaft F of the engine by means of a spiral gear 12 on the main crank shaft meshing with a spiral gear 14 on the valve stem D. As illustrated in Figs. 1, 4, 6 and 8, the valve is designed to be driven at one-fourth the speed of the main crank shaft. It may, however, if desired, be driven at one-half the speed of the engine or at less than one-fourth of the engine speed. The valve may also, if desired, be driven by means of a sprocket chain or other type of gearing from that illustrated. In a four cylinder engine such as illustrated the valve for the other two cylinders would ordinarily rotate in the opposite direction and have its ports arranged accordingly in order to cause the four cylinders respectively to act at the proper intervals.

In order to avoid end thrust on the valve and to provide ample port area I preferably provide two ports, G and H, from each cylinder to the valve. The ports G lead directly from beneath the valve to the respective cylinders while the ports H lead from the respective cylinders around the periphery of the valve and reach the upper face of the valve directly above the ports G through the cap 9. An exhaust port I leads from the periphery of the valve casing C to the exterior of the cylinder casting at 15 where the exhaust tube may be connected.

The valve E where designed to rotate at one-fourth engine speed, as indicated in Figs. 4 and 8, is a hollow shell divided by partitions 16 into three compartments, an intake compartment 17, which receives the fuel supply through a central port 18 in the cap 9, and conducts it through the chamber 17, and one or other of the passages 19 to the cylinder ports as the valve ports register therewith. As the exhaust passages 20

of the valve E respectively register with the cylinder ports, the cylinders are exhausted through the passages 20, chamber 21 and exhaust port I.

In order to secure tight joints between the face of the valve E and the terminals of the ports G, H and 18 I provide annular recesses 22 surrounding the terminals of said ports, in which recesses are movable rings 24, which closely fit and slide upon the terminal tubes 25 of said ports and have their faces 26 held in close contact with the rotating face of the valve E by means of springs 27 seated in said recesses 22. Thus while the valve E rotates freely in, and out of contact with the walls of the valve chamber, close joints are maintained between the respective stationary ports G, H and 18 and the disk-shaped faces of the valve E. The space between the faces of the valve and valve chamber are such as to facilitate the flow of a film of oil between said faces, which oil is supplied by a pump through oil ports 28 below and above the valve, E and which insures a supply of oil between the faces of the valve E and the rings 24. The tubes or annular projections 25 protect the rings 24 from direct contact with the heated gases passing through the ports, so that the rings 24 remain relatively cool and in condition to be lubricated, so that they are not liable to stick or set, or blow. I have illustrated two types of rings respectively in Figs. 5 and 9.

It is considered desirable that the valve be maintained at a moderately high and uniform temperature to insure all the fuel entering the cylinders in a vapor state, and this is attained by reason of the heating action of the exhaust upon the valve, which heating action, however, is modified and controlled by partially enveloping the valve chamber with water jacket spaces 30 of greater or less extent. Similar water jacket spaces 30' may, if desired, be provided in the cap 9, with connecting ports 31 leading from the water jacket of the cylinder casting to the water jacket spaces of the cap. For large engines water jacket spaces would be provided in the valve itself. Where the compensating ports H are employed the spark plugs N may be conveniently introduced through openings 32 to ignite the charge at that point, or may be introduced as usual into the cylinder.

In Figs. 10 and 11 I have illustrated a modification in which the compensating ports H are dispensed with and the valve connected with the cylinder ports G' through passages 19' and 20' in one face only of the valve, fuel being preferably supplied as heretofore described through a central port 18'. In this form of valve the end thrust on the valve is taken up by means of a thrust bearing 34 which is capable of ad-

justment to retain the valve in the desired position in the valve chamber and slightly out of contact with the walls thereof.

In Fig. 12 I have illustrated a valve E² designed to rotate at one-half the speed of the engine instead of at one-fourth of the engine speed. Said valve is designed to receive its fuel supply preferably through a central port, to conduct the fuel to the cylinder or cylinders successively through the port 19² and to exhaust the cylinder or cylinders through the port 20², as heretofore described. Said valve may be employed with single or with double or compensating ports as heretofore described.

The mechanism herein illustrated and described is capable of considerable modification without departing from the principle of my invention.

Having described my invention, what I claim is:

1. In combination with a pair of cylinders, a valve mechanism for combustion engine comprising a valve chamber at the closed ends of said cylinders, an intake port leading thereto independent ports leading therefrom directly to the respective cylinders, an exhaust port leading therefrom at one side, and a lubricant supply port, a valve 25 rotatable freely in said valve chamber and provided with a passage to connect said intake port successively with said cylinder ports and an independent passage to successively connect said cylinder ports with 30 said exhaust port.

2. A valve mechanism for combustion engines comprising a cylindrical valve chamber having a detachable cap to close one end thereof, an intake port leading centrally 40 through said cap to said valve chamber, a plurality of ports in the opposite end of said valve chamber between the axis and periphery of said chamber leading to separate engine cylinders, and an exhaust port leading 45 from the periphery of said valve chamber, a cylindrical valve rotatably mounted in said chamber and driven from the engine shaft in unison with the movements thereof, said valve being provided with a passage to connect said fuel supply port successively with said cylinder ports through a portion of the rotation of the valve, an independent passage to successively connect said cylinder ports with said exhaust port through a portion 55 of the rotation of the valve, and a face to close said cylinder ports through a portion of the rotation of said valve.

3. A valve mechanism for combustion engines comprising a valve chamber having a 60 port leading therefrom to the engine cylinder and an exhaust port leading therefrom, a valve rotatably mounted therein and provided with a passage to conduct a fuel supply to said cylinder port and a passage to connect said cylinder port with said exhaust

port, a valve stem driven from the engine shaft to rotate said valve, said valve stem being supported by a rigidly mounted bearing close to said valve, and by an adjustably mounted bearing at a greater distance from 70 said valve to provide for an accurate alignment of said valve with the inner face of said valve chamber.

4. In combination with a pair of cylinders, a valve mechanism for combustion engine comprising a valve chamber at the closed ends of said cylinders, an intake port leading thereto at one end, independent ports leading therefrom directly to the respective cylinders at the opposite end, an 75 exhaust port leading therefrom at one side, and a lubricant supply port, a valve rotatable freely in said valve chamber and provided with a passage to connect said intake port successively with said cylinder ports and an independent passage to successively 80 connect said cylinder ports with said exhaust port, annular recesses surrounding said valve chamber inlet and cylinder ports and annular members having sliding engagement with opposite walls of said recesses and yieldingly held in sliding contact with the face of said valve to secure tight joints surrounding said ports between said members and the face of the valve and between said members and the walls of said recesses.

5. A valve mechanism for internal combustion engines comprising a cylindrical valve chamber having a central intake port at one end, an exhaust port through its side, and a cylinder port at its opposite end, a hollow cylindrical rotary valve located in said valve chamber and divided by a partition into two compartments with intake 100 ports leading from opposite ends through one of said valve compartments, and exit ports leading from one end and one side through the other valve compartment.

6. A valve mechanism for combustion engines comprising a cylindrical valve chamber having an intake port, ports leading in pairs to the engine cylinder from positions opposite each other at each end of said chamber, and an exhaust port leading from the side 110 of said chamber, a hollow cylindrical valve divided by a partition into an intake passage and an exhaust passage to connect said intake and said exhaust ports respectively with said cylinder ports at different positions of the valve, said valve being rotatably mounted in said valve chamber, and means to introduce a lubricant into said valve chamber.

7. A valve mechanism for combustion engines comprising a cylindrical valve chamber having an intake port, ports leading in pairs to the engine cylinder from positions opposite each other at each end of said chamber, and an exhaust port leading from the side 125 130

- 4
- side of said chamber, a hollow cylindrical valve divided by a partition into an intake passage and an exhaust passage to connect said intake and exhaust ports respectively 40
- 5 with a pair of said cylinder ports at different positions of the valve, members having sliding engagement with said cylinder ports and yieldingly held in sliding engagement 45 with said valve to maintain tight joints between said ports and the faces of said valve, means to rotate said valve within said valve chamber in unison with the movements of the engine shaft, and means to introduce a lubricant into said valve chamber.
- 10 6. A valve mechanism for combustion engines comprising a cylindrical valve chamber having an intake port, ports leading in pairs to engine cylinders from positions opposite each other at each end of said chamber and an exhaust port leading from said chamber, a hollow cylindrical valve divided by a partition into an intake passage and an exhaust passage to connect said intake and exhaust ports respectively with a pair of said cylinder ports at different positions of the valve, members having sliding engagement with said cylinder ports and yieldingly held in sliding engagement with said valve to maintain tight joints between said ports and the face of said valve, and means to introduce a lubricant into said valve chamber. 50
- 15 7. A valve mechanism for internal combustion engines comprising a valve chamber having an intake port, a plurality of cylinder ports leading to separate cylinders and each serving as ingress and egress ports, and an exhaust port, and a rotary valve divided by a partition into independent compartments, an intake passage through one of said valve compartments to register with the respective cylinder ports, and an exhaust passage through the other valve compartment to register with the respective cylinder ports, said valve being driven by an indefinite speed ratio relative to the engine shaft. 60
- 20 8. A valve mechanism for combustion engines comprising a valve chamber having an intake port, ports leading in pairs to engine cylinders from positions opposite each other at each end of said chamber and an exhaust port leading from said chamber, a hollow cylindrical valve divided by a partition into an intake passage and an exhaust passage to connect said intake and exhaust ports respectively with a pair of said cylinder ports at different positions of the valve, members having sliding engagement with said cylinder ports and yieldingly held in sliding engagement with said valve to maintain tight joints between said ports and the faces of said valve, means to rotate said valve within said valve chamber in unison with the movements of the engine shaft, and means to introduce a lubricant into said valve chamber. 65
- 25 9. A compensating valve mechanism for combustion engines comprising a valve chamber having an intake port, ports lead-

- ing in pairs to engine cylinders from positions opposite each other in said chamber, and an exhaust port leading from said chamber, a hollow valve rotatably mounted in said chamber and divided by a partition into an intake passage and an exhaust passage, to connect said intake and exhaust ports respectively with a pair of said cylinder ports at different positions of the valve, members having sliding engagement with said intake and cylinder ports and yieldingly held in sliding engagement with said valve to maintain tight joints between said ports and the face of said valve, and means to introduce a lubricant into said valve chamber.
10. A valve mechanism for internal combustion engines comprising a valve chamber having an intake port, a plurality of cylinder ports leading to separate cylinders and each serving as ingress and egress ports, and an exhaust port, and a rotary valve divided by a partition into independent compartments, an intake passage through one of said valve compartments to register with the respective cylinder ports, and an exhaust passage through the other valve compartment to register with the respective cylinder ports, said valve being driven by an indefinite speed ratio relative to the engine shaft.

In testimony whereof I have affixed my signature in presence of two witnesses.

WILLIAM M. BAUMHECKEL.

Witnesses:

C. W. MILES,

W. THORNTON BOGERT.

It is hereby certified that in Letters Patent No. 1,220,814, granted March 27, 1917, upon the application of William M. Baumheckel, of Cincinnati, Ohio, for an improvement in "Valve Mechanisms for Internal-Combustion Engines," an error appears in the printed specification requiring correction as follows: Page 4, lines 66-67, claim 10, for the words "an indefinite" read *and in definite*; and that the said Letters Patent should be read with this correction therein that the same may conform to the record of the case in the Patent Office.

Signed and sealed this 17th day of April, A. D., 1917.

[SEAL.]

R. F. WHITEHEAD,
Acting Commissioner of Patents.

Cl. 123—52.
